CAN OPENER

Burton B. Hartman and Lloyd B. Hartman,
Wichita, Kans.

Application February 11, 1946, Serial No. 646,754

2 Claims. (Cl. 30—15.5)

1

Our invention relates to an improvement in can opener devices. One object of our invention is to provide a can opener that will cut the side of the can immediately below the end or top of the can and the top of the can will be held by the opener and be prevented from falling into the can.

A further object is to provide a can opener of the kind mentioned which, when the top of the can is cut therefrom, dirt, dust and the like will be prevented from falling into the contents of the can. This is a sanitary feature not provided for in can openers of the present day design and type.

A still further object is to provide a can opener of the kind mentioned that may be used as above stated and if the top of the can is not cut completely therefrom, the opener will have hold of the top and the remaining uncut portion of the side of the can may be bent in a hinge fashion by raising the can opener to lift the top of the can.

A still further object is to provide a can opener of the kind mentioned that is strong, durable and long lived, as well as one that is simple and not too expensive to make and sell. These and other objects will be more fully described as this description progresses.

Now referring to the accompanying drawings, in which similar numerals of reference designate the same parts throughout the several figures of the drawings:

Fig. 1 is a top plan view of our improved can opener.

Fig. 2 is a side view of the can opener.

Fig. 3 is a bottom plan view of the can opener.

Fig. 4 is a detail plan view of the can opener housing, the top plate of the housing being removed to show the parts contained in the housing.

Fig. 5 is a side view of the can opener showing the opener, in cutting position, on a can.

Fig. 6 is a top plan view of the can opener and can shown in Fig. 5.

Fig. 7 is a detail sectional view through the can opener, the view being taken along the line VII—VII in Fig. 2.

In the drawings the can opener device is shown as having a housing A comprising a bottom 10, sides 11 and 12, a front wall 13, a rear wall 14, and a cover plate 15 on which is integrally formed a handle support element 16 on which is rigidly mounted a handle element 16a. The cover plate 15 is rigidly held on the housing A by means of rivets 17, 18 and 19x which pass

through the bottom plate 10 and the cover plate 15.

The device is provided with a V-shaped sharp edged knife or cutter B that is integrally formed on, and as a part of a U-shaped support element 19, and the ends of the legs of the U-shaped element 19 are turned outwardly as at 19a, and the rivets 17 and 18 also pass through the out turned leg ends 19a to rigidly hold the U-shaped element 19 on the bottom plate 10, and support the knife B in a position spaced from the bottom plate 10 as shown in Fig. 2.

Positioned in the U of the U-shaped element 19 and resting against the outside of the bottom plate 10 is a flat faced roller 20 that is revolvably mounted on a rivet 21 that passes through the bend of the U-shaped element 19, the roller 20 and the bottom plate 10 of the housing A, and holds the roller 20 well behind the point of the knife B.

The rear wall 14, and side wall 12 of the housing A have an opening 22 therein and through which passes a bell-crank lever 23 that is pivotally carried on the housing rivet 19x. The end C of the bell-crank lever 23 is rockably positioned within the housing A while the end D of the bell-crank 23 projects from the housing A and along the handle element 16a and is rockable toward and away from the handle 16a.

In the housing A is a leaf spring 24, the central portion of which passes back of the rivet 17 and between the rivet 17 and side wall 1 and end wall 13 of the housing A, and one end of the spring 24 bears against the end wall 13 of the housing A while the other end of the spring 24 bears against the arm C of the bell-crank 23 so as to rock the lever portion C downwardly and the lever handle D outwardly from the handle 16a.

Revolvably mounted in the outer end of the lever portion C of the bell-crank 23 is a pin 25 that is in axial alignment with, and is integrally formed on one end of a shaft 25a, there being a shoulder 26 formed between the pin 25 and shaft 25a. A cross handle 27 is rigidly mounted on the other end of the shaft 25a and pin 25 may be revolved. A washer 28 is positioned around the pin 25 and bears against the shoulder 26 between the pin 25 and shaft 25a, and rests against the outside of the cover plate 15 of the housing A. The pin 25 passes through the cover plate 15 and bottom 10 of the housing A and is movable in arcuate slots 29 in the cover plate 15, and 30 in the bottom 10 of the

housing A, said arcuate slots are concentric with the rivet 19x.

A toothed feeder wheel 31 having a hub 32 that is integrally formed thereon is pressed on the lower end of the pin 25 and preferably welded thereto to insure rigidity between the pin 25 and the feeder wheel 31—32. The feeder wheel 31 revolvably rests against the outside surface of the bottom 10 of the housing A, and lies in the same plane with the roller 20.

The operation of the can opener device is as follows: The can opener is held over the top of a can and then moved downwardly in an inclined position, until the feeder wheel hub 32 rests on the top 33 of the can E, and the teeth of the feeder wheel 31 rests against the inside face of the upturned edge 34 of the can E, and the point of the cutter or knife B is directed toward the side of the can E at a point immediately below the top 33 of the can E. Now by pressing the bell-crank lever D toward the handle 16a, the feeder wheel 31 will be rocked toward the knife B and roller 20 as indicated by the dotted lines 25x in Fig. 3, whereupon the point of the knife B will have pierced the side of the can E and passed under the top 33 of the can E, and the rim or edge 34 of the can top will be firmly held between the teeth on the feeder wheel 31 and the roller 20. This having been done, the handle 27 may be turned to revolve the shaft and pin 25a—25, and the feeder wheel 31 which in turn will move or feed the wall of the can E against the knife B which will cut the can wall as indicated at F in Fig. 5. This operation may be continued until the top is entirely cut from the can and is held in the can opener; or the top of the can may not be cut from the can entirely, therefore the can opener may be rocked upwardly and the can top will go with it, and the uncut side portion of the can will bend in a hinge fashion and still hold the top on the can.

The can top having been cut as above described, the bell-crank lever end D may be released and the leaf spring 24 will press the lever end C rearwardly, whereupon the feeder wheel 31 will release its hold on the can top and the can opener may be readily removed from the can top.

Such modifications of our invention may be employed as lie within the scope of the appended claims without departing from the spirit and intention of our invention. Now having fully shown and described our invention, what we claim is:

1. In a can opener device of the kind described; said device having a housing element, said housing element having a handle and a U-shaped element having a pointed knife integrally formed thereon, a stop roller, said stop roller being positioned in the bend of the U-shaped knife carrying element and in rear of the point of the knife, a bell crank lever element, said bell crank lever element being pivotally mounted in said housing element, one end of said bell crank lever being rockable toward and away from the said handle, the other end of said bell crank lever being rockable within said housing in directions toward and away from said stop roller and the point of said knife, a shaft, said shaft being revolvably carried by the said other end of said bell crank lever and extending through and beyond the opposite sides of said housing, the sides of said housing having arcuate slots therein to receive the said shaft and to permit the movement of said shaft therein toward and away from said stop roller and the point of said knife, and means on one end of said shaft for revolving the shaft, a ratchet toothed feed wheel, said feed wheel being rigidly mounted on the other end of said shaft and revolvably resting against the outer face of the housing and being in alignment with the said stop roller; and means in said housing for yieldably rocking the said other end of said bell crank away from the said stop roller and knife.

2. In a can opener device of the kind described; the structure defined in claim 1, said means for yieldably rocking the last said end of the bell crank away from the stop roller and the point of the knife being a spring, one end of said spring bearing against one of the edge walls of said housing and the other end of said spring bearing against the last said other end of the bell crank.
